UNITED STATES PATENT OFFICE

134,408

DESIGN FOR A COMBINED SAND HOLDER, SPRAYER AND SHOVEL, AND FIRE SHIELD

Samuel A. de Waltoff, New York, N. Y.

Application August 29, 1942, Serial No. 108,075

Term of patent 14 years

To all whom it may concern:

Be it known that I, Samuel A. de Waltoff, a citizen of the United States, residing at New York, in the county of New York and State of New York, have invented a new, original, and ornamental Design for a Combined Sand Holder, Sprayer and Shovel, and Fire Shield, of which the following is a specification, reference being made to the accompanied drawing, forming a part thereof, in which

Figure 1 is a side elevational view of a combined sand holder, sprayer and shovel, and fire shield, showing my new design.

Figure 2 is a front view slightly in perspective thereof.

Figure 3 is a rear view slightly in perspective thereof.

Figure 4 is a cross-sectional view taken on line 4—4 of Figure 2.

I claim:

The ornamental design for a combined sand holder, sprayer and shovel, and fire shield, as shown.

SAMUEL A. DE WALTOFF.
